ABSTRACT: A pitless well adapter comprises an elongate body having a fitting in its lower end for connection to the well pipe and having a fitting at the upper end for connection to a pull pipe. The body has two end flanges and a central flange, and the exterior surface between these flanges presents two tapered portions. One tapered portion flares downwardly and outwardly from the upper end flange, while the other tapered portion flares downwardly and outwardly from the central flange. When the adapter is installed, O-ring seals will roll along the flared surfaces and seat within grooves, so that the adapter is mounted in sealed relation within the well casing.

PITLESS WELL ADAPTER

SUMMARY OF THE INVENTION

An object of this invention is to provide a pitless well adapter comprising a single piece body having flared exterior surface portions upon which the O-ring seals will roll into seated relation during installation of the adapter to thereby facilitate installation of the pitless adapter. The O-ring seals engage the interior surface of the well casing so that the outlet of the adapter is effectively sealed from the exterior. The O-rings are loosely positioned around the body and are sealingly interposed between the adapter and the well casing only when seated in the grooves of the adapter body. With this arrangement, the O-ring seals may be urged past obstructions in the well casing during installation because of the unique construction of the pitless well adapter body.

Suitable recesses are provided in the pitless well adapter body so that shifting the well adapter slightly upwardly, the O-rings which are snugly seated within the annular grooves in the body, will move into the recesses and permit removal of the adapter from the well casing. The present pitless well adapter is therefore adapted for easy installation and removal from a well casing, as well as providing a highly efficient sealed coupling between the well pipe and the lateral line.

BRIEF DESCRIPTION OF THE FIGURES OF THE DRAWING

FIG. 1 is a vertical sectional view of the novel pitless well adapter illustrated in an initial position during installation thereof;

FIG. 2 is a view similar to FIG. 1 but illustrating the pitless well adapter in an intermediate position during installation thereof;

FIG. 3 is a view similar to FIGS. 1 and 2 but illustrating the pitless well adapter in the installed position; and

FIG. 4 is a view similar to the previous views but illustrating the relationship of the parts during removal of the pitless well adapter from the well casing.

DETAILED DESCRIPTION OF THE INVENTION

Referring now to the drawings, it will be seen that one embodiment of the novel pitless well adapter, designated generally by the reference numeral 10, is there shown. This pitless well adapter is of the type which serves to couple the conduit connected to the submersible pump with the lateral line or conduit which is positioned below the frost line. With this arrangement, it will be noted that the well casing 11 is provided with a lateral outlet fitting 12 which, as shown, is located below the frost line L, and the lateral conduit is adapted to be connected in communicating relation to this fitting. The well casing projects slightly above the surface of the ground, and the pitless well adapter is introduced through the upper end of the casing and intercommunicates the conduit connected to the submersible pump with the lateral conduit.

The pitless well adapter 10 includes an elongate hollow body 13 preferably formed of a suitable rigid material such as metal, plastic or the like, and having an internal wall 14 integrally formed therewith which divides the interior of the body into a chamber 15 and a chamber 16. The lower end portion of the body has an integrally threaded fitting 17 formed therat which actually defines the inlet of the pitless well adapter. It will be noted that the internal wall 14 together with a depending portion of the body actually forms the fitting 17. The fitting 17 is connected to the upper threaded end of a conduit 18 which extends downwardly into the well casing and is connected at its lower end in communicating relation with respect to a submersible pump (not shown).

The upper end of the body 13 has an internal threaded fitting 19 integrally formed therewith which is connected in threaded relation with the lower threaded end of a riser or pull pipe 20. The upper end portion of the pull pipe is provided with a coupling 21 and this coupling may be closed by a suitable plug when the pitless well adapter is in a completely in-

stalled position or it may be connected to other lengths of pull pipe during installation and removal of the adapter. When the adapter is in the installed position, the coupling 21 engages a retainer member 22 in sealed relation therewith, the retainer sealingly engaging the upper end of the well casing.

It will be noted that the fitting 17 and the fitting 19 are disposed in coaxial relation with respect to each other and that an opening 23 formed at the lower end of the body at one side of the fitting 17. This opening communicates with the chamber 16, and electrical conductors 24 extend upwardly from the pump through the opening 23 and extend through the chamber 16 and finally through pipe 20. These conductors are connected to a source of electrical current to operate the pump in a well known manner. It will be noted that the conduit 18 is intercommunicated with the chamber 15 and is sealed with respect to the chamber 16.

The body 13 is provided with an upper annular flange 25 which is integrally formed therewith and which projects outwardly therefrom adjacent the upper end thereof. A lower annular flange 26 is integrally formed with the body adjacent the lower end thereof and projects radially outwardly therefrom. An intermediate flange 27 is integrally formed with the body intermediate the ends thereof and projects outwardly therefrom. The intermediate flange 27 is spaced equidistant from the flanges 25 and 26. It will be noted that the flanges are of the same size and are of a size substantially smaller than the interior of the casing. It will also be noted that the body has an opening 15a therein intermediate the ends thereof and this opening 15a communicates with the chamber 15 of the body.

The hollow body, while being of circular cross-sectional configuration, includes an upper tapered exterior surface portion 28 which flares outwardly and downwardly from the upper flange 25 towards the intermediate flange 27. The exterior surface of the body also defines a second tapered portion extending from the intermediate flange 27 and flaring outwardly and downwardly towards the lower flange 26. The upper tapered portion 28 terminates downwardly in an upper annular groove or seat 30 which is located adjacent but spaced from the intermediate flange 27. The lower tapered portion 29 terminates downwardly in a lower annular groove or seat 31 which is spaced from but closely adjacent the lower flange 26. It is pointed out the length of the upper tapered portion is identical to the length of the lower tapered portion. It is also pointed out that the upper and lower tapered portions are of substantially identical frustoconical configuration.

An upper annular recess 32 is located between the lower end of the upper tapered portion and flange 27, and a lower annular recess 33 is located between the lower flange 26 and the lower tapered portion 29. The cross-sectional size of the body through the recesses is substantially smaller than the size of the body through the tapered portions including the seats or grooves in the tapered portions. An upper annular O-ring 34 engages in the seat or groove 30 and a lower O-ring seal 35 engages in the seat or groove 31 when the adapter is in the fully installed position. When so installed, it will be noted that the O-rings sealingly engage the inner surface of the well casing, as best seen in FIG. 3, to define an exterior chamber 36 that communicates with the opening 15a in the body 10 and communicates with the outlet 12 in the casing.

During installation of the pitless well adapter, the fitting 12 of the casing 11 will be connected in communicating relation with a lateral conduit. The pitless well adapter will have its lower fitting 17 connected to the conduit 18 which in turn is connected to the pump. The fitting 19 will be connected to the pull pipe 20. The coupling 21 of the pull pipe, with the plug removed, may be connected to additional pull pipe sections as best seen in FIGS. 1 and 2.

The O-ring 34 will be loosely positioned around the upper tapered portion while the O-ring 35 will be loosely positioned around the lower tapered portion. In this regard, O-ring 34 will be positioned against the upper end flange 25 while the lower O-ring 35 will be positioned against the lower surface of the intermediate flange 27.

As the pitless well adapter is inserted into the casing, the O-rings will slide along the interior of the well casing and because of the loose arrangement of the O-rings with respect to the body, these O-rings will traverse any inwardly projecting obstructions such as a weld or the like. This is very important during the installation of a pitless well adapter. These O-rings will be held against the respective upper and intermediate flanges respectively until the pitless well adapter is moved downwardly beyond its correctly located position, as best seen in FIG. 2. Thus the adapter is lowered to a point below the lateral outlet and this distance corresponds to the length of the respective tapered portions. Thereafter, when the adapter is pulled in an upward direction into the correct position, the O-rings are rolled downwardly along the tapered portion and will seat in the upper end lower grooves or seats, as best seen in FIG. 3. When this occurs, the exterior chamber 36 is defined between the well casing and the exterior surface of the body, and this exterior chamber intercommunicates with the opening 15a and the lateral opening in the casing. Thus water under pressure passing upwardly through the conduit 18 will circulate through the exterior chamber 36 as well as the interior chamber 15 and this pressure condition will prevent any tendency of water from the exterior from seeping into the chamber 36. However, the O-rings 34 and 35 provide excellent seals to seal against any seepage of water or the like into the chamber 36. As pointed out above, the upper end of the casing is also sealingly closed. However, the well itself may be vented through the pull pipe since certain state codes require venting of the well.

In the event that it is desirable to remove the adapter from the well casing, it is merely necessary to pull upwardly on the pull pipe and the two O-rings will then drop into the recesses 32 and 33, respectively, and the adapter may thereafter be very easily pulled from the well casing.

From the foregoing, it will be seen that I have provided a novel pitless well adapter of single-piece construction which utilizes a pair of O-ring seals to seal the adapter in place in the well casing.

It will further be noted that the uniquely constructed body of the pitless well adapter permits installation of the adapter even though the well casing may have inwardly projecting obstructions. My novel pitless well adapter not only permits precise location of the adapter with respect to the lateral outlet but also is arranged and constructed to facilitate ready removal of the adapter from the well casing.

Thus it will be seen that I have provided a pitless well adapter which is not only of simple and inexpensive construction but one which functions in a more efficient manner than any heretofore known comparable device.

I claim:

1. A pitless well adapter for use within a well casing having a lateral outlet therein located below the surface of the ground,

comprising:
 a hollow elongate body adapted to be vertically oriented in a well casing;
 an internal wall located interiorly of said body and integral therewith and dividing the interior into a pair of chambers, one of said chambers having an outlet opening therein for communicating with a lateral outlet in the well casing;
 means at the lower end of said body defining an inlet communicating with said one chamber and adapted to be connected in communicating relation with a conduit connected to a submerged pump;
 an outwardly projecting upper element integrally formed with said body adjacent the upper end thereof;
 an outwardly projecting lower element integrally formed with said body adjacent the lower end thereof;
 an intermediate element integral with said body intermediate the ends thereof and projecting outwardly therefrom;
 said body having an exterior surface including a first portion increasing in cross-sectional size from said upper element to adjacent the intermediate element, a second portion increasing in cross-sectional size from said intermediate element to adjacent said lower element;
 said first tapered portion terminating downwardly in a first annular groove;
 said second portion terminating downwardly in a second annular groove;
 a pair of yieldable O-ring members one of which is seated in said first annular groove and the other of which is seated in said second annular groove and being engageable in sealing relation with the inner surface of a well casing when the adapter is positioned therein to define a sealed chamber including said one chamber and intercommunicating said outlet opening with the lateral outlet in the casing; and
 attachment means at the upper end of said tubular body adapted to be connected to the lower end of a pull pipe.

2. The pitless well adapter as defined in claim 1 wherein said first portion and said second portion each has substantially the same length dimension and each uniformly increases in cross-sectional size in a downward direction.

3. The pitless well adapter as defined in claim 1 wherein said upper, lower, and intermediate elements each comprises an annular flange integral with the body projecting outwardly therefrom, and said flanges are of substantially the same size.

4. The pitless well adapter as defined in claim 1 and a first annular recess in the exterior surface of said body located between said intermediate element and said first annular groove, and a second annular recess in the exterior surface of said body located between said lower element and said second annular groove.
